UNITED STATES PATENT OFFICE.

EDWARD F. GRAY, OF NEW YORK, N. Y., ASSIGNOR TO GILL BROTHERS COMPANY, OF STEUBENVILLE, OHIO, A CORPORATION OF WEST VIRGINIA.

DESIGN FOR A SHADE-BOWL.

45,337.

Specification for Design.

Patented Mar. 3, 1914.

Application filed December 9, 1913. Serial No. 805,649. Term of patent 7 years.

To all whom it may concern:

Be it known that I, EDWARD F. GRAY, a citizen of the United States of America, and a resident of 16 East Forty-seventh street, New York city, New York, have invented a certain new, original, and ornamental Design for a Shade-Bowl, of which the following is a specification.

Referring to the drawings, Figure 1 is an elevation showing the bowl in upright position. Fig. 2 is a bottom plan of the same.

The shade consists of a bowl 1, the polar zone 2 of which is fluted. Above the fluted portion is a scroll 3, the upper portion adja-

cent the rim bearing a design 4 consisting of a human face flanked by figures of fabulous animals resembling a winged sea-horse and a winged sea-lion.

I claim:

The ornamental design for a shade bowl substantially as shown and described.

Signed by me at 16 E. 47 St. N. Y. city this 28 day of November, 1913.

EDWARD F. GRAY.
